UNITED STATES PATENT OFFICE

NIELS E. WERNBERG, OF FRANKLIN, PENNSYLVANIA, ASSIGNOR TO CHICAGO PNEUMATIC TOOL COMPANY, OF NEW YORK, N. Y., A CORPORATION OF NEW JERSEY

SAFETY APPARATUS FOR INTERNAL-COMBUSTION ENGINES

Application filed August 28, 1928. Serial No. 302,505.

This invention relates to prime movers particularly internal combustion engines of the type which have force feed circulation of a medium adapted to lubricate or to cool the engine.

One object of the invention is to provide apparatus for stopping the engine in the event of failure or serious impairment of the circulating system. Another object is to make such apparatus simple and readily applicable to both old and new engines. Another object is to secure positive operation of such apparatus. Further objects will be apparent from the detailed description which follows.

In order to illustrate the invention, one concrete embodiment thereof is shown in the accompanying drawings in which:

Fig. 1 is a side elevational view of an internal combustion engine equipped with the invention;

Fig. 2 is a side elevational view partly cut away of the lower portion of the fuel feeding means disclosed in Fig. 1;

Fig. 3 is a fragmentary sectional view substantially on the line 3—3 of Fig. 2 and showing a portion of the top or cylinder member of the fuel feeding device.

The embodiment of the invention chosen for the purpose of illustration is shown in relation to a multi-cylinder prime mover A of the internal combustion type. The engine shown is of the six cylinder Diesel type, provided adjacent one end with fuel feeding means or pumping apparatus B which has a fuel pump cylinder for each cylinder of the engine. The engine also provides a circuit through which a liquid medium is circulated. This circuit may be either the water cooling system or the force feed lubricating system. In the present instance the lubricating system is the one illustrated and comprises an engine-driven lubricant pump 4 which discharges through a pipe 5 into a lubricant manifold 6 extending the length of the engine and also adapted to be supplied manually with lubricant under pressure when the engine is to be started through a hand-operated pump 7 which discharges into manifold 6 through pipe 8.

In order to protect the engine against dam-

age which may result from operating with an insufficient supply or distribution of lubricant, means are provided for automatically stopping the engine in the event of loss of pressure in the lubricating circuit. The means for this purpose are disclosed in detail in Figs. 2 and 3. The safety device, as shown, is applied to the fuel pump apparatus and is arranged to render the same inoperative when the lubricant pressure falls to a predetermined minimum. To this end a reciprocable shaft 9 is mounted in bearings 10 and 11 in the base of fuel pumping apparatus B. Bearing 10 is provided by a cylinder member 12 which is threaded into an opening in the base of the pumping apparatus and provides a chamber 12a which is partly closed by a perforated plate 13 having a threaded extension 13a to which is secured a cylindrical cap 14. Shaft 9 extends through chamber 12a, through the perforation in plate 13 and into the chamber provided by cap 14, a head 15 being suitable pinned or otherwise secured to the extreme end of shaft 9. Interposed between head 15 and plate 13 is a heavy coil spring 16 which normally urges and maintains shaft 9 at the limit of its movement to the right. Shaft 9 has a key 13c engaging a slot 13b in plate 13 to prevent the shaft from turning and has a piston 17 which makes a close sliding fit in chamber 12a. The right hand side of piston 17 is arranged to be subjected to the pressure in the force feed lubricating system of engine A through an inlet pipe 18 which connects with manifold 6 (Fig. 1). A drain 19 takes care of any leakage past piston 17 by conducting it by a pipe 19 into the cam housing of engine A. Lubricating oil pressure which reaches chamber 12a through the perforation or bore in plate 13 thrust against piston 17, thereby overcoming and compressing spring 16, and moves shaft 9 to the left to the position shown in Fig. 2 and maintains it in this position. If for any reason the oil pressure drops below the minimum allowed by spring 16, the latter will overcome the oil pressure and move shaft 9 to the right. This movement will stop the engine by mechanism now to be described.

Shaft 9 has a series of cuts or notches 20, 20a, 20b, 20c, 20d and 20e, six in number, corresponding to the number of fuel pump and engine cylinders. These notches, in the running position of the engine (Fig. 2), receive corresponding and cooperating plungers 21, 21a, 21b, 21c, 21d and 21e with a clearance. Immediately to the left of the notches are slants or cam surfaces 22, 22a, 22b, 22c, 22d and 22e which engage and lift the plungers when spring 16 moves shaft 9 to the right. Since the plungers and the mechanism actuated thereby are the same for each pump cylinder, description of one will suffice, the section shown in Fig. 3 corresponding to a section through any one of the six plungers. Plunger 21 is differential in form and makes a close sliding fit in the differential bore of a guide member 23, which extends through the wall of the fuel chamber 24 of the pumping apparatus. Plunger 21 has a central bore receiving in partly telescoping engagement and with a close sliding fit, a second plunger member 25 which is provided with a head 25a. Interposed between head 25a and plunger 21 and encircling the stem of plunger 25 is a coil spring 26 which establishes a resilient connection between the two plungers and yieldingly resists further telescoping engagement of the same. The plungers are disposed directly beneath the inlet valve *a* which is normally held closed by a spring *b* which is sufficiently light to enable the inlet valve to be suction operated. The opening of inlet valve *a* admits fuel to passage *c* which extends to the fuel pump and the amount of the fuel admitted, which becomes available for the cylinder charge may be arranged to be varied in accordance with the usual practice by governor control means of any suitable type indicated at *d*.

From the above it will be apparent that when the oil pressure fails and spring 16 moves shaft 9 to the right, cam surface 22 will engage plunger 21 and move the latter together with plunger 25 supported thereby into contact with the stem end of inlet valve *a*, overcoming the spring *b* and forcing and holding the inlet valve open so that there is a mere surging or by-passing of the fuel around inlet valve *a* and none of the charge reaches the engine cylinder, thus stopping the engine. The function of the resilient-telescoping connection of the first and second plunger members 21 and 25 is to enable shaft 9 to move to the right when one or more of the inlet valves *a* is subjected momentarily to a heavy pressure through the action of the pump piston (not shown). In such an instant the upper plunger remains substantially stationary after engaging the end of valve *a*, the movement of the lower plunger 21 being permitted by the telescoping engagement of the two plungers and the resilient connection provided by spring 26. The inlet valves

not subject to heavy pressure will be opened and the engine will stop. The long bearing surfaces between first plunger 21 and its guide 23 and between second plunger 25 and first plunger 21 with the tight fits therein maintaining, prevent leakage of fuel from chamber 24. The cam shaft 27 shown in Fig. 3 as extending through fuel chamber 24 and which is similar in all respects to shaft 9, is arranged for manual operation to enable the operator to stop the engine at will by by-passing the fuel around the inlet valve.

While a preferred form of the invention has been herein shown and described, it is to be understood that the invention is not limited to the specific details thereof but covers all changes, modifications, and adaptations within the scope of the appended claims.

I claim as my invention:

1. The combination with an internal combustion engine having a force feed circulating system, of means controlled by the pressure in said system for affecting the fuel supply to the engine comprising a reciprocable shaft, a by-pass valve for the fuel supply, and a plunger having relatively yieldable parts actuated by said shaft for opening said valve.

2. The combination with an internal combustion engine having a force feed circulating system, of means controlled by the pressure in said system for affecting the fuel supply to the engine comprising a by-pass valve for the fuel supply, a shaft in line with the axis of said valve and movable transversely thereof, a member arranged to engage said valve, and a cam projection on said shaft for actuating said member to open said valve.

3. The combination with an internal combustion engine having a force feed circulating system, of means controlled by the pressure in said system for affecting the fuel supply to the engine comprising a reciprocable shaft, a by-pass valve for the fuel supply movable in a direction transverse to the movement of said shaft, and a resilient plunger actuated by said shaft for opening said valve.

4. The combination with an internal combustion engine having a force feed circulating system, of means controlled by the pressure in said system for affecting the fuel supply to the engine comprising a reciprocable shaft, a by-pass valve for the fuel supply, a multi-part plunger arranged to be actuated by said shaft for opening said valve, and a resilient connection between the parts of said plunger.

5. The combination with an internal combustion engine having a plurality of cylinders, fuel feeding means for each of said cylinders and a circuit through which a liquid medium is circulated under pressure, of means for stopping the engine upon loss of pressure in said circuit comprising a reciprocable shaft subjected to the pressure in said

circuit, a series of inlet valves for the fuel feeding means movable transversely of the axis of said shaft, and means associated with said shaft for opening all of said valves simultaneously.

6. The combination with an internal combustion engine having a plurality of cylinders, fuel feeding means for each of said cylinders and a circuit through which a liquid medium is circulated under pressure, of means for stopping the engine upon loss of pressure in said circuit comprising a reciprocable shaft subjected to the pressure in said circuit, a series of inlet valves for the fuel feeding means, and means controlled by said shaft for simultaneously opening all of said valves but permitting one or more of them to remain closed without interfering with the opening of the other valves.

20 7. The combination with an internal combustion engine having a plurality of cylinders, fuel feeding means for each of said cylinders and a circuit through which a liquid medium is circulated under pressure, of means for stopping the engine upon loss of pressure in said circuit comprising a reciprocable shaft subjected to the pressure in said circuit, a series of inlet valves for the fuel feeding means, said shaft being movable transversely of the axis of said valves, and means actuated by said shaft including a series of plungers for simultaneously opening said valves.

8. The combination with an internal combustion engine having a plurality of cylinders, fuel feeding means for each of said cylinders and a circuit through which a liquid medium is circulated under pressure, of means for stopping the engine upon loss of pressure in said circuit comprising a reciprocable shaft subjected to the pressure in said circuit, a series of inlet valves for the fuel feeding means, and a series of plungers actuated by said shaft for opening said valves, each plunger being resiliently contractable to permit one or more of said valves to remain closed without interfering with the movement of said shaft.

9. The combination with an internal combustion engine having a plurality of cylinders, fuel feeding means for each of said cylinders and a circuit through which a liquid medium is circulated under pressure, of means for stopping the engine upon loss of pressure in said circuit comprising a reciprocable shaft subjected to the pressure in said circuit, a series of inlet valves for the fuel feeding means, a series of plungers for engaging said valves, said shaft being disposed beneath said plungers and movable transversely thereof, and a series of cams on said shaft for engaging said plungers to move the latter to open said valves.

10. In combination with a fuel pump for a Diesel engine a suction operated inlet valve

for said pump, means arranged to engage said valve to open the same and render the pump inoperative, a reciprocable shaft for actuating said means, resilient means for moving said shaft to valve opening position, and means arranged to be subjected to pressure fluid to overcome said resilient means and leave said valve free to operate. 70

11. In combination with a fuel pump for a Diesel engine a suction operated inlet valve for said pump, means arranged to engage said valve to open the same and render the pump inoperative, a reciprocable shaft for actuating said means, a spring for moving said shaft to valve opening position, a chamber for pressure fluid adjacent said shaft, and means subjecting said shaft to the thrust of pressure fluid in said chamber to overcome said spring and leave said valve free to operate. 75

12. In combination with a fuel pump for a Diesel engine a suction operated inlet valve for said pump, means arranged to engage said valve to open the same and render the pump inoperative, a reciprocable shaft for actuating said means, a spring for moving said shaft to valve opening position, and a piston on said shaft arranged to be subjected to pressure fluid to overcome said spring and leave said valve free to operate. 80

13. The combination with a multi-cylinder fuel pump for a multi-cylinder Diesel engine, a suction actuated inlet valve for each of said pump cylinders, plungers arranged to engage said valves to move the same to open position, means movable transversely of said plungers for actuating the same, and opposed resilient and fluid pressure means for actuating said means. 85

14. The combination with a multi-cylinder fuel pump for a multi-cylinder Diesel engine, a suction actuated inlet valve for each of said pump cylinders, plungers arranged to engage said valves to move the same to open position, a shaft reciprocable transversely of said plungers having a series of cams for actuating said plungers, and opposed resilient and fluid pressure means for actuating said shaft. 90

15. The combination with a fuel pump for a Diesel engine, said pump providing a fuel chamber, a valve controlling the fuel passing from said chamber to the pump proper, a guide member extending through the wall of said chamber, a plunger slidably supported by said member, a second plunger in telescoping engagement with said first plunger, a resilient connection between said plungers, and means for actuating said first plunger to cause said second plunger to engage said valve. 105

16. The combination with a fuel pump for a Diesel engine, said pump providing a fuel chamber, a valve controlling the fuel passing from said chamber to the pump proper, a 110

- guide member extending through the wall of said chamber, a plunger slidably supported by said member, a second plunger in partial telescoping engagement with said first plunger, a spring yieldingly resisting further telescoping movement of said plungers, and means for actuating said first plunger to cause said second plunger to engage said valve.
- 10 17. The combination with a fuel pump for a Diesel engine, said pump providing a fuel chamber, a valve controlling the fuel passing from said chamber to the pump proper, a guide member extending through the wall 15 of said chamber and having a differential bore, a differential plunger fitting the bore of said guide member, a second plunger partly telescoping within a bore in said first plunger, a coil spring encircling a portion 20 of said second plunger and arranged to resist further telescoping movement of said plungers, and a cam member arranged to engage said first plunger to move said second plunger to engage said valve.
- 25 Signed by me at Franklin, in the county of Venango and State of Pennsylvania, this 20th day of August, 1928.
